(57) **CLAIM**

The ornamental design for a vehicle light, as shown and described.

DESCRIPTION

FIG. 1 is a perspective view of a vehicle light, showing my new design;

FIG. 2 is an another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of portion “9” of FIG. 2.

The dash-dash broken lines in the drawings illustrate portions of the article that form no part of the claimed design. The dash-dot-dot broken lines illustrate the boundary of the portion shown enlarged in FIG. 9.
